UNITED STATES PATENT OFFICE.

HARRY H. KRONE, OF CHICAGO, ILLINOIS.

BOOT-BLACK STAND.

1,271,588.

Specification of Letters Patent. Patented July 9, 1918.

Application filed July 2, 1917. Serial No. 178,164.

To all whom it may concern:

Be it known that I, HARRY H. KRONE, a citizen of the United States, and a resident of the city of Chicago, county of Cook, and State of Illinois, have invented certain new and useful Improvements in Boot-Black Stands, of which the following is a specification.

My invention relates to improvements in boot black stands, and has for its object the provision of an improved construction of this character, which is readily foldable for easy transportation.

The invention consists in the combinations and arrangements of parts hereinafter described and claimed.

The invention will be best understood by reference to the accompanying drawings, forming a part of this specification, and in which,

Figure 1 is a vertical longitudinal section of a boot black stand, embodying my invention,

Fig. 2, a top plan view of the same,

Fig. 3, a front view of the same,

Fig. 4, a section of the stand shown in folded condition,

Fig. 5, a horizontal section taken through the post of a seat employed in the construction, and

Fig. 6, a slightly modified form of construction.

The form of construction illustrated in Figs. 1 to 5, inclusive, comprises a body 7 in the form of a rectangular wooden box having a slidable drawer 8 therein for containing the boot black utensils and materials. A foot rest 9 is secured to the top of the body 7, said foot rest being in substantially U form, as indicated, to provide a longitudinal channel therethrough. The body 7 is supported at its rear on supporting legs in the form of an open work frame 10, hinged to the bottom of said body at 11 by

means of a hinge which prevents outward swinging of said frame, as indicated. The frame 10 carries a brace 12 pivoted to the inner side thereof, and adapted, when extended, to rest against the bottom of the body 7 to prevent inward upward folding of the leg frame 10. The forward portion of the body 7 is supported by means of another leg frame substantially in U form and angularly bent to form vertically extending

portions 13 pivoted at 14 to the sides of the front of the body 7, and a horizontally ex-

tending portion 15 having knee pads 16 on the sides thereof, said knee pads being used by the operator in blackening shoes, as will be readily understood. A suitable seat 17 is also provided on body 7, said seat being supported on a hollow seat post 18 hinged at 19 to the top of said body. The seat post 18 carries a slidable bolt 20 operable by means of a knob or handle 21 projecting through a slot therein, said bolt being adapted to fit within a hollow handle member 22 on the rear of the body 7.

By this arrangement, it will be observed that when the seat is arranged in vertical position for use, the bolt 20 may be readily engaged with the handle member 22 and the seat locked in such position. When it is desired to fold the seat, bolt 20 is moved upwardly to disengage handle 22 whereupon the seat may be folded downwardly into the channel in foot rest 9. Likewise the leg frame 10 may be readily folded against the bottom of the box and leg frame 13—15 readily folded over the top of the box, all as indicated in Fig. 4. This arrangement furnishes a simple and convenient form of boot black stand, which may be readily folded into compact form for convenience in transportation.

In the modified form indicated in Fig. 6 a foldable operator seat 23 is mounted on a seat post or frame 24 pivoted to the frame 15 for convenience of the operator as will be readily understood.

While I have illustrated and described the preferred forms of construction for carrying my invention into effect, these are capable of variation and modification without departing from the spirit of the invention. I therefore, do not wish to be limited to the precise details of construction set forth, but desire to avail myself of such variations and modifications as come within the scope of the appended claims.

Having described my invention what I claim as new and desire to secure by Letters Patent is:

1. A boot black stand comprising a body; a foot rest on the top of said body having a channel extending therethrough; and a foldable seat post on the rear of said body adapted to fold into said channel, substantially as described.

2. A boot black stand comprising a body; a foot rest on the top of said body having a channel extending therethrough; a fold-

able seat post on the rear of said body adapted to fold into said channel; a slideable bolt in said seat post; and a hollow member at the rear of said body adapted to receive said bolt, substantially as described.

3. A boot black stand comprising a body; supporting legs for the rear of said body; and a combined supporting frame and operator support, foldably connected at the front of said body, said frame being substantially in U form and angularly bent to form a horizontal portion adapted to rest upon the ground and a vertical portion adapted to constitute supporting legs for said body, said vertical portion being pivoted to the front of said body, substantially as described.

4. A boot black stand comprising a body; a foot rest on the top of said body; supporting legs for the rear of said body; and a combined supporting frame and operator support, foldably connected at the front of said body, said frame being substantially in U form and angularly bent to form a horizontal portion adapted to rest upon the ground and a vertical portion adapted to

constitute supporting legs for said body, said vertical portion being pivoted to the front of said body and said frame being adapted to fit over said foot rest, substantially as described.

5. A boot black stand comprising a body; a foldable hollow seat post connected with said body; a bolt in said seat post; and a hollow socket on said body adapted to receive said bolt to hold said seat post in upright position, substantially as described.

6. A boot black stand comprising a body; a foldable support for said body, said support being angular in form to constitute a horizontal portion adapted to rest upon the ground and a vertical portion pivoted to said body to constitute supporting legs therefor; and an operator support on said horizontal portion, substantially as described.

In testimony whereof, I have signed my name to this specification in the presence of two subscribing witnesses.

HARRY H. KRONE.
